UNITED STATES PATENT OFFICE.

ALBERT OPPENHEIM, OF NEW YORK, N. Y., ASSIGNOR TO THE CONNECTICUT WEB & BUCKLE COMPANY, OF BRIDGEPORT, CONNECTICUT, A CORPORATION OF CONNECTICUT.

BUCKLE.

Application filed March 6, 1924. Serial No. 697,179.

To all whom it may concern:

Be it known that I, ALBERT OPPENHEIM, a citizen of the United States, residing at New York, county of New York, State of New York, have invented a new and useful Buckle, of which the following is a specification.

This invention relates to an improved buckle and means for securing a web there-
to, and has for an object to provide an im-
proved construction of buckle and securing
means which will not cut or tear the fabric
of the web, but will securely hold it so that
there will be no slipping under strain, and
which will securely fasten the free end of
the web to the buckle without the necessity
of stitching.

With the foregoing and other objects in
view, I have devised the construction il-
lustrated in the accompanying drawing
forming a part of this specification, corre-
sponding reference characters being employed
throughout the various figures to indicate
corresponding elements. In this drawing,
Fig. 1 is a top plan view of a section of a
supporter showing my improved buckle ap-
plied thereto.

Fig. 2 is a longitudinal section through
the center showing the buckle open.

Fig. 3 is a similar view showing the buckle
closed.

Fig. 4 is a front elevation of the buckle in
open position.

Fig. 5 is a transverse section thereof sub-
stantially on line 5—5 of Fig. 4.

Fig. 6 is a front elevation of the buckle
in closed position with a portion of the lever
broken away to more clearly show the con-
struction and operation.

Fig. 7 is a view similar to Fig. 5 showing
the end of the web secured by stitching.

Fig. 8 is a view similar to Fig. 5 showing
the use of a different type of clip, the section
being substantially on line 8—8 of Fig. 9,
and

Fig. 9 is a view similar to Fig. 4 showing
a slightly different construction of frame
and the clip shown in Fig. 8.

I have shown at 10 a section of any suit-
able type of web carrying any suitable type
of clasp 11 for connection to the garment to
be supported. The buckle is of the so-called
rustless type, comprising a frame, prefer-
ably of wire, composed of spaced front and

back portions 12 and 13 respectively, which
are connected by side members 14. The
front portion may extend throughout the
length of the buckle but is preferably com-
posed of relatively short ends, as shown, to
which the lever is pivoted.

The lever comprises the usual front or
finger piece 15 and the securing tongue 16.
In the embodiment illustrated this tongue
is shaped in cross section substantially as
that disclosed in the patent to Brannigan
No. 1,454,666, dated May 8, 1923, in which
the tongue extends forwardly under the fin-
ger piece from its pivot toward the back por-
tion of the frame when the lever is in secu-
ring position, and is then bent laterally either
toward or from the finger piece at 17 and
terminates in a plain edge 18. The distance
between the bend and the plain edge is such
as to provide a clamping surface 19 which
acts when the buckle is in closed position to
clamp the web against the back portion 13
of the frame. This surface is preferably
substantially normal to a line 20 joining the
centers of the front and back portions of the
frame and is so located that the bend 17 and
the plain edge 18 lie on opposite sides of
this line when the lever is in securing po-
sition. This will securely clamp the web
against the back portion of the frame, and
as the bend 17 and the plain edge 18 are on
opposite sides of the line 20 it will be ob-
vious that strain on the web will tend to
clamp the web more securely because move-
ment of the lever about its pivot will tend
to move either the bend 17 or the plain edge
18 more securely against the back of the
frame.

To assist the tongue in more securely
fastening the web I provide the back por-
tion with a pair of spaced bends or kinks
extending toward the front portion provid-
ing a pair of offsets 21, and the width of
the tongue 16 is made such that when the
lever is turned to clamping position this
tongue will pass between these offsets and
will clamp the web against the opposed sides
22 of these offsets, as well as against the
intermediate portion of the back of the
frame. The ends of the tongue are prefer-
ably inclined or rounded, as shown at 23, so
as to lie substantially parallel with the sides
of the offsets, as shown in Fig. 6. It will be
apparent that this construction, when the

lever is moved to securing position, will place a double lateral bend in the web at the opposite ends of the tongue so that strain on the web will tend to draw it laterally or at right angles to the direction of the strain as well as longitudinally, and will give a much greater securing effect. The bends or offsets 21 are wider in the plane of the back than the thickness of the back member about which the end of the web may be stitched if desired, as shown at 25 in Fig. 7.

In order to eliminate the usual stitching operation, and thus cut down the manual operations required and to reduce the amount of web required to secure the buckle to the web, I may incline the side members 14 of the frame toward each other from the front portion 12 toward the back portion 13 substantially as indicated in Figs. 4 and 6, so that the opening through the frame is of greater length adjacent the front portion than it is adjacent the back portion. I then secure to the free end of the web a rigid clip 24. This clip is preferably a substantially U-shaped piece of sheet metal embracing the free end of the web and clamped thereto by merely pressing the sides together. These sides may if desired be provided with openings or projections struck up therefrom to extend into the web to give a stronger holding effect. I have not shown these projections as it is believed this feature would be obvious. The length of this clip, however, is less than the longest part of the opening through the frame of the buckle but greater than the shortest part of this opening so that the clip may be passed through the frame through the longest part of the opening, as shown in dotted lines in Figs. 4 and 5, and then when moved laterally to the shortest side of this opening, as shown in full lines in these figures, the ends of the clip will engage the side members 14 and prevent withdrawal of the end of the web from the buckle, securely fastening the same thereto without requiring any stitching operation. This securing means is much more reliable than the stitching because it will not pull out, as stitching is liable to do, besides being easier and cheaper to assemble, but it may, however, be easily disconnected if desired. There is no danger of this clip becoming accidentally disconnected from the buckle because after the body of the web is passed through the frame of the buckle, as shown in Figs. 2 and 3, it tends to hold the free end of the web in the lower portion of the frame, and this action is assisted by the tongue of the buckle.

In Figs. 8 and 9 is shown how the bends forming the offsets 21 may be used with a metal clip for securing the free end of the web. By using a corrugated clip, as shown at 26, that is one in which the free edges 27

are corrugated, the free ends of the offsets 21 will engage these corrugated edges and retain the end of the web as shown in Figs. 8 and 9. With this construction the inclined sides of the frame, as shown at 14, in Fig. 4, are not necessary. With the construction, as shown in Figs. 8 and 9, the clip may be of less length than the width of the web so that there are no free ends of the clip extending beyond the edge of the web.

Having thus set forth the nature of my invention, what I claim is:

1. A buckle comprising a frame having spaced front and back portions, said back portion having a pair of spaced offsets adjacent the opposite ends thereof extending toward the front portion, and a lever hinged to the front portion and provided with a tongue having a plain free edge adapted to pass through the frame and clamp a web against the intermediate portion of the back and the opposed sides of the offsets.

2. A buckle comprising a frame having spaced front and back portions, said back portion having a pair of spaced substantially V-shaped offsets adjacent the opposite ends thereof extending toward the front portion, and a lever hinged to the front portion and provided with a tongue having a plain free edge adapted to pass through the frame and clamp a web against the intermediate portion of the back and the opposed sides of the offsets.

3. A buckle comprising a frame having spaced front and back portions, said back portion having a pair of spaced substantially V-shaped offsets adjacent its opposite ends extending toward the front portion, and a lever hinged to the front portion and provided with a tongue having a plain free edge adapted to pass through the frame and extend between the offsets and inclined at its opposite ends adjacent said offsets, said tongue being adapted to clamp a web against the intermediate portion of the back and the opposed sides of the offsets.

4. A buckle comprising a frame having spaced front and back portions, said back portion having a pair of spaced offsets adjacent the opposite ends thereof extending toward the front portion, and a lever pivoted to the front portion of the frame and provided with a finger piece and a tongue extending forwardly under said finger piece from the pivot toward the back portion of the frame when the lever is in securing position and terminating in a plain edge, said tongue being bent laterally at a distance from said plain edge to form a surface adjacent the back portion of the frame extending at substantially right angles to a line joining the front and back portions of the frame when the lever is in securing position, said surface being of such a length that the

bend and plain edge are on opposite sides of this line and the web is clamped against the intermediate portion of the back of the frame by said surface, the web being also 5 clamped against said offsets by the ends of the tongue.

5. A buckle comprising a wire frame having spaced front and back portions, said back portion being bent laterally to form a 10 pair of spaced offsets adjacent its opposite ends extending toward the front portion, and a lever pivoted to the front portion provided with a finger piece and a tongue extending forwardly under the finger piece 15 from the pivot toward the back portion of the frame when the lever is in securing position and terminating in a plain edge, said tongue being bent laterally at a distance from said plain edge to form a surface adjacent the back portion of the frame adapted 20 to clamp a web against the intermediate portion of the back, said tongue being of a length to pass the plain edge thereof between the offsets and clamp the web there- 25 against.

6. A buckle comprising a wire frame having spaced front and back portions, said back portion being bent laterally to form a pair of spaced offsets adjacent its opposite 30 ends extending toward the front portion, and a lever pivoted to the front portion provided with a finger piece and a tongue extending forwardly under the finger piece from the pivot toward the back portion of 35 the frame when the lever is in securing position and terminating in a plain edge, said tongue being bent laterally at a distance from said plain edge to form a surface adjacent the back portion of the frame extending through the frame and substantially 40 normal to the plane of the frame when the lever is in securing position, said surface being of such a length that the bend and plain edge are on opposite sides of the 45 frame and the web is clamped against the back portion of the frame by said surface, said tongue being of such a length as to pass the plain edge thereof between said offsets and clamp the web thereagainst.

50 7. A buckle comprising a frame having spaced back and front portions, said back portion being bent laterally to form a pair of spaced offsets extending toward the front portion, and a lever pivoted to the front portion provided with a finger piece and a tongue extending forwardly under the finger piece from the pivot toward the free edge thereof, said tongue being then bent laterally away from the finger piece and 55 terminating in a plain edge spaced from said bend adapted to pass between the front

and back portions of the frame adjacent the back portion of the frame when the lever is moved to web securing position, the distance between the bend and plain edge being 65 such as to form a clamping surface adjacent the back and adapted to clamp a web against the intermediate portion of the back of the frame, and the tongue being of such a length that the ends therefor are adapted to clamp 70 the web against the opposed sides of the offsets.

8. A buckle comprising a wire frame including spaced front and back portions joined by side members, the back portion 75 being bent laterally adjacent the side members to provide spaced offsets extending toward the front portion, a web extending through the frame, a rigid clip secured to the end of the web and having a free edge 80 engaging said offsets to hold said web, and a lever pivoted to the front portion of the frame and provided with a tongue adapted to coact with the back portion and the offsets to clamp the run of the web. 85

9. In combination, a buckle comprising a frame having spaced front and back portions joined by side members, a web extending through the frame, a rigid clip secured to the end of the web, said clip being of 90 less length than the distance between the side members of the frame and provided with a corrugated free edge engaging the offsets to hold the web, and a securing lever pivoted to the front portion of the frame. 95

10. In combination, a buckle comprising a frame having spaced front and back portions joined by side members, the back portion being bent laterally intermediate its ends to provide one or more offsets extending toward the front portion, a web extending through the frame, a substantially U-shaped clip embracing the end of the web and secured thereto, said clip having a corrugated free edge adapted to engage the offset or offsets to hold the web, and a securing lever pivoted to the front portion of the frame. 100 105

11. In combination, a buckle comprising a frame having spaced front and back portions, said back portion being provided with one or more offsets extending toward the front portion, a web extending through the frame, and a rigid clip secured to the end of web, said clip having raised portions extending outwardly from the web to engage the ends of the offsets to hold the web, and a securing lever pivoted to the front portion of the frame. 110 115

In testimony whereof I affix my signature.

ALBERT OPPENHEIM.
